UNITED STATES PATENT OFFICE.

GEORGE C. FROWNFELTER, OF JOSHUA, TEXAS.

CATTLE-GUARD.

SPECIFICATION forming part of Letters Patent No. 739,165, dated September 15, 1903.

Application filed May 2, 1903. Serial No. 155,367. (No model.)

To all whom it may concern:

Be it known that I, GEORGE C. FROWNFELTER, a citizen of the United States, residing at Joshua, in the county of Johnson and State 5 of Texas, have invented new and useful Improvements in Cattle-Guards, of which the following is a specification.

This invention relates to certain new and useful improvements in railway cattle-guards, 10 and the well-known purpose of the same is to guard railway-tracks at a crossing against stock straying onto the track and also to serve for a like purpose at other points along a railway-track, as in divisions between fenced 15 land.

The invention consists in the novel construction and arrangement of the several parts, which will be more fully hereinafter described and claimed.

20 In the drawings, Figure 1 is a top plan view of a portion of a railway-track and the improved guard shown applied thereto. Fig. 2 is a longitudinal vertical section through a portion of the guard. Fig. 3 is a transverse 25 vertical section of one of the guard strips or slats.

Similar numerals of reference are employed to indicate corresponding parts in the several views.

30 The numerals 1 and 2 designate railway-track rails, between which are disposed the main guard-sections embodying the features of the invention, and outside of the rails are similar sections to take up the space between 35 the rails and fence-posts or guard-fences adjacent to the rails. Each of the sections comprises a series of longitudinally-disposed strips or slats 5 of similar construction and arranged parallel and held in regular spaced 40 relation by transverse blocks 6. The strips or slats 5 abut against the opposite ends of the transversely-extending space-blocks 6 and also are partially embedded in the latter, and extending longitudinally through the blocks 45 to secure the strips or slats against movement and displacement are bolt-rods 7, as clearly shown by Fig. 2. These bolt-rods are headed at one end and receive nuts on their opposite ends, and by this means they can be 50 detached at any time after a primary assemblage of the several parts to replace a strip

or slat which may become injured or broken without affecting the practical use of the remaining portion of each section, and thereby economize in guard constructions.

55

Each slat or strip 5 has the lower main body portion thereof substantially rectangular in cross-section, as clearly shown by Fig. 3, and the opposite sides at the upper extremity of the strip are cut away to form a triangular top 8 and produce a sharp edge 9. At regular intervals spikes 10 are driven through the body of the strip alternately from opposite sides and at upward reverse angles of inclination, care being taken to have the spikes considerably longer than the maximum width of the portion of the strip through which they are driven and also to have the extremities of the spikes which stand free at opposite sides of the strip come 70 out from the latter at the base of the inclined sides of the triangular top. The free extremities of the spikes are then struck upwardly at an obtuse angle to the main body portion thereof held within the strip, so that 75 the pointed ends 11 will be exposed for engagement on opposite sides of the top 8 below the plane of the upper sharpened edge 9 of the said top. The strips or slats 5 will be formed, preferably, of wood and are arranged 80 at such distance apart that the hoof of an animal walking thereover will be pressed down between the strips or slats and the points of the free or upstruck extremities of the spikes will prick the hoof of the animal 85 in a tender portion thereof and cause the animal to desist from an attempt to walk over the guard-sections. The triangular tops of the several strips also render the foothold of an animal unstable, and it will be impossible for the latter to cross the guard or even 90 mount the same with all four feet, in view of the fact that as soon as the forefeet engage the strips or slats and become pricked by the free extremities of the spikes the animal will 95 back off.

To render it more difficult to mount the guard-sections, the opposite ends of the strips or slats are beveled downwardly and outwardly, as at 12, and the foot of an animal 100 coming in contact therewith will slip off, as will be readily understood.

The improved device is simple and effective in its construction and operation and can be readily set up in operative position.

Changes in the form, proportions, and minor details of construction may be resorted to without departing from the spirit of the invention.

Having thus fully described the invention, what is claimed as new is—

- 10 1. A cattle-guard comprising a series of slats with upper sharpened edges, and spike extremities disposed on opposite sides of, and at a distance below, the plane of the said edges.

2. A cattle-guard comprising a series of 15 longitudinally-disposed slats having upper sharpened edges, and spikes alternately driven through opposite sides of the slats at upward angles of inclination in reverse directions and their free pointed extremities 20 exposed and bent upwardly on the opposite sides of the upper portions thereof.

In testimony whereof I affix my signature in presence of two witnesses.

GEORGE C. FROWNFELTER.
